UNITED STATES PATENT OFFICE.

JACOB S. BROWN, OF LOS ANGELES, CALIFORNIA, ASSIGNOR BY DIRECT AND MESNE ASSIGNMENTS, OF ONE-HALF TO WALTER F. EICHENHOFER, OF LOS ANGELES, CALIFORNIA.

UNDERREAMER.

Application filed March 24, 1922. Serial No. 546,350.

To all whom it may concern:

Be it known that I, JACOB S. BROWN, a citizen of the United States, residing at Los Angeles, in the county of Los Angeles and 5 State of California, have invented new and useful Improvements in Underreamers, of which the following is a specification.

My invention relates to underreamers for enlarging the bore of well holes to permit 10 the lowering of the casing, and a purpose of my invention is the provision of an underreamer having cutters of extremely durable construction; adequate bearing surfaces to withstand the various strains to which the 15 parts are subject in operation; efficient and simple means for maintaining the cutters in expanded position for underreaming, and providing for their positive collapsing while being inserted into or withdrawn from the 20 well hole; and means for allowing of the ready disassembling or removal of the cutters.

I will describe one form of underreamer embodying my invention and will then point 25 out the novel features thereof in claims.

In the accompanying drawings,

Figure 1 is a view showing in front elevation one form of underreamer embodying my invention.

30 Figure 2 is a view showing the underreamer in side elevation.

Figure 3 is a vertical longitudinal sectional view of the underreamer shown in the preceding views with the cutters in contracted position.

Figures 4 and 5 are views showing in side elevation and top plan, respectively, one of the cutters comprised in the underreamer shown in the preceding views.

40 Figure 6 is a view similar to Figure 3 showing the cutters in expanded position.

Figure 7 is a transverse sectional view taken on the line 7—7 of Figure 6.

45 Figure 8 is an enlarged detail view showing the inner side of the closure disc shown in Figure 7 together with the spring.

Figure 9 is a view similar to Figure 8 showing the outer side of the disc and the latter turned against the tension of the 50 spring to align the disc opening with respect to the stock opening.

Figure 9^a is a vertical sectional view showing in detail the stock embodied in the underreamer shown in the preceding views.

Figures 10 and 11 are transverse sectional views taken on the lines 10—10 and 11—11 of Figure 9^a.

Figure 12 is a bottom plan view of the stock shown in Figure 9^a.

Similar reference characters refer to similar parts in each of the several views.

Referring specifically to the drawings and particularly to Figure 9^a, the underreamer is shown as including a stock or body designated generally at S and provided with 65 a longitudinal extending bore 15 communicating at its lower end with a bore 16 of smaller diameter to provide at the junction of the two an annular shoulder 17. The lower portion of the stock is formed at diametrically opposed points with longitudinal extending slipways 18 communicating at 70 their upper ends with sockets 19 having inclined surfaces 20 which function as guides as will be hereinafter described. The wall 75 separating the slipways 18 and the bore 16 is slotted longitudinally as indicated at 21 and at diametrically opposed points to communicate with the slipways. As shown in Figures 9 and 12, the lower end of the stock 80 is recessed as indicated at 22 to form a head 23 which constitutes the bottom of the bore 16. The head 23 is formed with a threaded bore 24 adapted for the reception of a screw. The side faces of the head provide vertical 85 shoulders.

Referring now to Figures 3 and 6, the bore 15 of the stock S is shown as receiving a rod 25 threaded at its upper end to receive a nut 26 and beneath which latter is arranged a 90 washer or ring 27. The lower end of the rod is provided with a plunger 28 adapted for sliding movement within the bore 16. A coiled expandible spring 29 is arranged within the bore 15 and in surrounding relation 95 with respect to the rod 25. This spring 29 is interposed between the washer 27 and a washer 30 engaging with the shoulder 17, this arrangement causing the spring to normally urge the rod and consequently the 100 plunger upwardly within the stock. As shown in Figure 3, the plunger 28 is formed with a transversely extending slot 31 in which lugs 32 are adapted to work in effecting the movement of cutters K to expanded or contracted position.

Each cutter includes a bit 33 formed on the lower end of a shank 34. On the upper end of the shank 34 a

head 35 is formed which is adapted to work within the corresponding socket 19. The shank 34 is formed with flat sides and an inner edge which is inclined as indicated at 5 34^a with its lower end extending inwardly to provide a thrust shoulder 34^b. Below the shoulder 34^b flat bearing surfaces 34^c are formed on projections at the junction of the shank and bit, these surfaces being adapted 10 to engage the shoulders on the head 23 when the cutters are in expanded position as shown in Figure 6.

For limiting the downward movement of the plunger 28 to allow of the cutters occupying contracted position but to prevent disassembling or removal of the cutters from the stock, a threaded pin or screw 36 is fitted within the opening 24 of the head 23 with its upper tapered end projecting 20 into the bore 16 and thereby defining the lowermost position of the plunger 28. This pin 36 is adjustable vertically within the head 23, and when adjusted downwardly so that its upper end is flush with the upper 25 surface of the head 23, the plunger can occupy a position wherein the heads 35 are completely removed from the sockets 19 thereby allowing the removal of the cutters K from the stock.

30 To maintain the plunger in this lowermost position wherein the cutters can be removed, I provide a rod or pin 37 having a handle 38 which, as clearly shown in Figure 7, is extended through suitable openings 35 formed in a closure disc 39, stock S, and the plunger 28, it being understood that these openings are in registration only when the plunger is in its lowermost position. To prevent the passage of oil, mud, or other 40 foreign matter into the stock through these openings, the closure disc 39 is rotatably sustained within a recess formed in the stock S by means of a screw 40. The opening 41 is normally out of registration with 45 the stock opening so as to close the latter and prevent the passage of foreign matter into the stock. The disc is retained in this position by means of a spring 42 which, as clearly shown in Figure 8, is coiled intermediate its ends to embrace the hub of the disc while its ends are extended to engage shoulders 43 formed by recessing the under side of the disc. The tension of the 50 spring is such as to allow the manual turning of the disc to move the opening 41 into registration with the stock opening as is clearly shown in Figure 9.

The operation of the underreamer is as follows: As the cutters K normally occupy 60 fully expanded position under the action of the spring 29, it is necessary in order to insert the underreamer into the well casing to force the plunger 28 downwardly to the position shown in Figure 3 in order that the cutters can be moved to contracted position.

The attendant pulls down on cutters K and the plunger is held in this lowered position by employing the rod or pin 37 as has been described. In moving the cutters to contracted position, the lugs 32 engage the 70 plunger 28 so as to move it and consequently the cutters downwardly until the bearing surfaces 34^c are disengaged from the head 23 thereby allowing an inward movement of the cutters until the surfaces 34^c contact 75 with each other as is clearly shown in Figure 3. In this position of the cutters the heads 35 are not completely withdrawn from the sockets 19 so that when downward pressure upon the plunger is relieved, the spring 80 can operate in elevating the cutters to expanded position, it being understood that the ends of the heads engage the inclined surfaces 20 so as to be guided back into the 85 sockets 19.

When the cutters are in contracted position the underreamer can be readily inserted into the well casing, and this operation having been completed the pin 37 is withdrawn but as the well casing retains the cutters in contracted position the spring now fails to function. After passing the underreamer downwardly through the well casing, the cutters automatically move to expanded position under the action of the spring 29 95 when the cutters have passed below the well casing. During the movement of the cutters from contracted to expanded position, the thrust shoulders 34^b wipe the lower edges of the head 23 thereby effecting the 100 gradual expansion of the cutters as they move upwardly. In the completely expanded position of the cutters, the bearing surfaces 34^c contact with the opposite sides of the head 23 and cooperate with the heads 35 and the sockets 19 in effectively bracing the cutters in fully expanded position so that the underreamer is now ready for operation. 105

Although I have herein shown and described only one form of underreamer embodying my invention, it is to be understood that various changes and modifications may be made herein without departing from the spirit of the invention and the spirit and scope of the appended claims. 110

What I claim is:

1. An underreamer comprising a stock having slipways formed therein and sockets at one end of the slipways, a head between the slipways, a plunger movable in the stock and having an opening formed therein, cutters mounted in the slipways and including shanks and heads formed on the shanks adapted to fit in said sockets, lugs formed on the shanks and engaging within the opening of said plunger, thrust shoulders formed on the shanks and engagable with said head to effect expansion of the cutters when the plunger is moved in one direction, 125 130

and means for urging the plunger to a definite position wherein the cutters are held in expanded position.

2. An underreamer comprising a stock 5 having slipways formed therein and sockets at one end of the slipways, a plunger movable in the stock between the slipways and sockets to occupy two extreme positions, said plunger being formed with an opening, a 10 head formed in the stock between said slipways, cutters mounted in the slipways, heads formed on the cutters adapted to fit within said sockets, lugs formed on the cutters engaging within the opening of said plunger, 15 thrust shoulders and bearing surfaces formed on the cutters and adapted to engage said head for moving the cutters to expanded or contracted position upon movement of said plunger, means for urging the 20 plunger to one extreme position in which the heads are disposed within said sockets and the bearing surfaces are in contact with said head, and an adjustable member mounted in said head for defining the other 25 extreme position of said plunger.

3. An underreamer comprising a stock, cutters mounted in the stock to occupy expanded and contracted positions, a plunger operatively connected to the cutters and 30 movable in the stock to occupy one position in which the cutters are expanded and another position in which the cutters are contracted, said stock and plunger being formed with openings adapted to register when the 35 plunger is in the second mentioned position, a closure plate movable to control the opening of said stock and normally urged to a position in which the stock opening is closed, and a tool adapted to be inserted through 40 said plate and the openings of said stock and plunger for retaining the plunger in the second mentioned position.

4. An underreamer comprising a stock, cutters mounted in the stock to occupy expanded and contracted positions, a plunger operatively connected to the cutters and 45 movable in the stock to occupy one position in which the cutters are expanded, a second position in which the cutters are contracted, 50 and a third position in which the cutters can be removed from the stock and plunger,

adjustable means for defining the last two positions of the plunger, and means for urging the plunger to the first mentioned position.

5. An underreamer comprising a stock having slipways formed therein, a plunger movable in the stock between the slipways to occupy two extreme positions, a head formed in the stock between said slipways, 55 cutters mounted in the slipways and engageable by said plunger so as to be moved to expanded or contracted position, means for urging the plunger to one extreme position in which said cutters occupy expanded position, and an adjustable member mounted in said head for defining the other extreme position of said plunger.

6. An underreamer comprising a stock having slipways formed therein, a plunger 70 movable in the stock between the slipways to occupy two extreme positions, a head formed in the stock between said slipways, cutters mounted in the slipways and engageable by said plunger so as to be moved to 75 expanded or contracted position, means for urging the plunger to one extreme position in which said cutters occupy expanded position, and a screw plug mounted in said head for defining the other extreme position of 80 said plunger.

7. An underreamer comprising a stock, having slipways formed therein which communicate with the lower end of the stock, the lower end face of the stock being recessed, a head formed in the stock adjacent to and in the recesses and having side shoulders between the lower ends of the slipways, a plunger movable in the stock between the slipways and above the head, a screw mounted vertically through the head to engage the plunger and adjustably limit the movement of the plunger toward the head, and cutters mounted in the slipways and engageable by the plunger, said cutters being 85 formed with extensions having side faces to engage the shoulders for defining the expanded position of the cutters.

In testimony whereof I have signed my name to this specification.

JACOB S. BROWN.
